DESIGN FOR A CASKET

Harry S. Scholl, Chicago, Ill., assignor to F. H. Hill Company, Inc., Cleveland, Ohio, a corporation of Ohio

Application March 24, 1936, Serial No. 61,768

Term of patent 14 years

To all whom it may concern:

Be it known that I, Harry S. Scholl, a citizen of the United States, residing at Chicago, in the county of Cook and State of Illinois, have invented a new, original, and ornamental Design for a Casket, of which the following is a specification, reference being had to the accompanying drawing, forming a part thereof.

Referring to the drawing:

Fig. 1 is a side elevational view; and
Fig. 2 is an end elevational view of a casket, showing my new design.

I claim:

The ornamental design for a casket, as shown.

HARRY S. SCHOLL.
